UNITED STATES PATENT OFFICE.

FRANZ X. WAGNER, OF NEW YORK, N. Y., ASSIGNOR TO UNDERWOOD TYPEWRITER COMPANY, OF NEW YORK, N. Y., A CORPORATION OF NEW JERSEY.

TYPE-BAR CONSTRUCTION.

SPECIFICATION forming part of Letters Patent No. 758,197, dated April 26, 1904.

Application filed April 13, 1903. Serial No. 152,297. (No model.)

To all whom it may concern:

Be it known that I, FRANZ X. WAGNER, a citizen of the United States, and a resident of the borough of Manhattan, city, county, and State of New York, have invented certain new and useful Improvements in Type-Bar Construction, of which the following is a specification.

My invention relates to the type-bars of type-writers and other machines, and has for its object, first, to enable a type-bar to be readily removed from the machine without disturbing the other type-bars, and, second, to enable the distance between the pivot and the type to be accurately adjusted.

To this end my invention consists of certain features of construction and combinations of parts, as will be fully described hereinafter, and particularly pointed out in the appended claims.

Reference is to be had to the accompanying drawings, in which—

Figure 1 is a sectional elevation of a portion of a type-writer embodying my improvements. Fig. 2 is a plan of the type-bar. Fig. 3 is a cross-section on line 3 3 of Fig. 2. Fig. 4 is a detail view of the pivot portion of the type-bar and its support, drawn upon an enlarged scale; and Fig. 5 is a partial rear elevation of the segment, showing the cover-plate.

A indicates the portion of the machine-frame to which the key-lever B is pivoted at B'.

C' indicates a pin-and-slot connection between the key-lever and an elbow-lever C, fulcrumed at C'. This elbow-lever has a pin-and-slot connection D' with a type-bar pivoted at D² upon the segment E, which also carries the type-bar guide F, extending adjacent to the point where the type strikes the platen G. The manner of actuating the type-bar is immaterial to my invention.

A' is a cushion for supporting the type-bars in their position of rest.

The pivot D² is of angular shape and fits into slots E' of the segment E, substantially of key-hole form—that is, said slots are widened at their inner ends, so that the pivots may turn therein; but the outer portions of the slots are

relatively narrow, so that the pivots can be slid therethrough in a predetermined position only, as will be obvious from Fig. 4. A cover-plate H, having teeth H' to close the rear ends of the keyhole-slots E', may be provided, if desired, this plate being secured to the segment E. When it is desired to remove a type-bar, the cover-plate H is removed or at least swung out of the way, and the elbow-lever C is lifted from its pivot C² and disengaged from the type-bar, whereupon the latter may be removed rearward without disturbing its neighbors.

In order that each type may strike the platen at the same point, I so construct the type-bar that the distance between the pivot and the type may be adjusted, and to facilitate this adjustment I provide a gage device which is practically automatic in its action. For this purpose the type-bar consists of two sections, a rear section or pivot-section D and a front section D³, carrying the type J. These sections have a sliding connection with each other, so that the type-bar is extensible and the distance from the pivot D² to the type J may be varied. The connection may, for instance, be made by means of a screw K, screwing into the type-section D³ and extending through a longitudinal slot D⁴ of the pivot-section D. To brace the type-bar, its sections may be bent to form longitudinal ribs D⁵ D⁶, one of which fits into the other. (See Fig. 3.)

So far as described the construction allows the distance between the pivot D² and the type J to be varied; but a proper adjustment would require relatively considerable time and skill on the part of the operator. To facilitate the adjustment, I provide an automatic gage device which comprises a beveled pin L, arranged on the type-section D³, and a guide-aperture F' on a stationary part. Preferably the pin L is located adjacent to the type J and the guide F' on the type-bar guide F.

It will be understood that when the pin L is within the guide F' the type J occupies the correct position relatively to the platen G. The operation of this part of my invention is as follows: At the time the type-bars are first put in the machine the two sections are

roughly adjusted so that the type will be in approximately the right position. Then the screw K is somewhat loosened, so as to still hold the sections D D' together in their rough 5 adjustment, yet allow the type-section D' to slide outward or inward if a push or pull is exerted on said type-section. Thereupon the type-bar is swung against the platen by depressing the key-lever B. Now by reason of 10 the inclined or beveled shape of the pin L if said pin should not enter the guide F' centrally a deflecting or wedge action will occur and the type-section D' will automatically be shifted to the proper position. The screw K 15 will then be tightened, preferably while the type-bar is in its vertical or printing position.

Various modifications may be made without departing from the nature of my invention. Thus it will be obvious that the position 20 of the pin K and guide F' may be reversed, locating the beveled pin upon a stationary part and the guide on the type-section D'. Instead of the pin the guide may be beveled, or both members of the gage device may 25 be beveled.

I claim as my invention and desire to secure by Letters Patent—

1. In a type-writer or other machine, a support having keyhole-slots, a type-bar having 30 an angular pivot arranged to enter said slots, and a movable cover-plate provided with teeth arranged to normally close the open ends of said slots.

2. In a type-writer or other machine, a pivoted type-bar, the type of which is movable 35 toward and from the pivot, in combination with a gage device consisting of two members, one of which is stationary while the other is

connected with the type-bar, to control the adjustment of the type relatively to the pivot 40 of the type-bar.

3. In a type-writer or other machine, a pivoted type-bar, the type of which is movable toward and from the pivot, in combination 45 with a gage device consisting of a pin member and a guide member, one of said members being stationary while the other is connected with the type-bar, said members being adapted by their engagement to control the adjustment of the type relatively to the pivot of 50 the type-bar.

4. In a type-writer or other machine, a type-bar consisting of two sections, a pivot-section and a type-section, one of said sections being provided with a groove and the other section 55 having a laterally-projected, longitudinally-extending rib adapted to fit into said groove, said section being arranged to slide in the said groove for the purpose of adjustment.

5. In a type-writer or like machine, a type-bar consisting of two sections, a pivot-section and a type-section, one of said sections being provided with a groove and the other section having a laterally-projected, longitudinally-extending rib adapted to fit into said groove, 65 said section being arranged to slide in the groove for the purpose of adjustment and means for locking the two sections together.

In testimony whereof I have signed my name to this specification in the presence of two sub- 70 scribing witnesses.

FRANZ X. WAGNER.
